(57) CLAIM

The ornamental design for an ornament for face protector, as shown and described.

DESCRIPTION

FIG. 1 is a front view of an ornament for face protector showing my new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof; and,

FIG. 7 is a side view of FIG. 2.

The portions of the face protector not shown in the drawings or described in the specification form no part of the claimed design.
